UNITED STATES PATENT OFFICE.

WILLIS E. ROYS, OF NEW YORK, N. Y.

RADIATOR.

No. 830,369.

Specification of Letters Patent.

Patented Sept. 4, 1906.

Application filed September 14, 1906. Serial No 278,505.

To all whom it may concern:

Be it known that I, WILLIS E. ROYS, a citizen of the United States, residing at Richmond Hill, New York, in the county of New York and State of New York, have invented certain new and useful Improvements in Radiators; and I do declare the following to be a full, clear, and exact description of the invention, such as will enable others skilled in the art to which it appertains to make and use the same.

My invention relates to improvements in radiators of that class made of corrugated metal and adapted to be secured upon the walls of rooms or other places to be heated.

The object of the invention is to provide a steam or hot-water radiator of this character which will be simple, durable, and efficient in construction and which may be manufactured at comparatively small cost.

With the above and other objects in view the invention consists of certain novel features of construction, combination, and arrangement of parts, as will be hereinafter described and claimed.

In the accompanying drawings, Figure 1 is a front elevation of my improved radiator. Fig. 2 is a horizontal sectional view through the same, taken on the plane indicated by the line 2 2 in Fig. 1. Fig. 3 is a vertical sectional view taken on the plane indicated by the line 3 3 in Fig. 1, and Fig. 4 is a detail vertical longitudinal sectional view through one end of the radiator.

The embodiment of my invention shown in the accompanying drawings is in the form of a steam-radiator designed to be attached to the wall of a room, so as to take up but little space. This radiator comprises front and rear sheets 1 and 2 of corrugated iron or other metal, which have their side edges seamed together, as shown at 3, and their top and bottom ends or edges connected by casting upon them a top 4 and a bottom 5. The corrugations of the front and rear sheets 1 2 may be of any form and arrangement; but I preferably make them substantially V-shaped, so that they fit into each other, as clearly shown in Fig. 2 of the drawings. The two sheets may be spaced apart, so as to leave a steam-space between them, by any suitable means; but I preferably place one or more pieces of

soft wire or the like 6 between them before they are riveted together, as shown at 7. The double seam 3 at the vertical or side edges of the sheets 1 2 may also be of any form that will provide a water and steam tight connection. After the sheets 1 and 2 have been riveted together and seamed along their sides their ends are placed in molds in which the top 4 and bottom 5 are cast. This top 4 and bottom 5 close the steam-space between the sheets 1 2, and a circulation through said space is effected by tapping the bottom 5 adjacent to its ends, as shown at 8 6; 9, to receive the supply and return pipes 10 and 11.

Any suitable ornamental work 12 may be secured upon the top 4 or other portions of the radiator, and the latter may be secured to a wall by brackets 13 or in any other suitable manner.

The construction and advantages of the invention will be readily understood from the foregoing description, taken in connection with the accompanying drawings. It will be seen that by making the front and rear of the radiator of corrugated sheet metal, seaming their side edges, and casting the top and bottom on the same, as shown and described, a very light and at the same time durable radiator is provided which may be manufactured at comparatively small cost.

Various changes in the form, proportion, and the minor details of construction may be resorted to without departing from the principle or sacrificing any of the advantages of this invention.

Having thus described my invention, what I claim as new, and desire to secure by Letters Patent, is—

The herein-described radiator comprising a top, a bottom, front and rear sheets having their upper and lower edges secured respectively to the top and bottom, their vertical end edges secured together, and their intermediate portions vertically corrugated; the front sheet having its corrugations extending into those of the rear sheet, and its end portions bent to form, together with the end portions of the rear sheet, vertical flow and return chambers, rivets connecting the corrugated portions of the sheets together, and longitudinally-disposed spacing-strips be-

tween the corrugated portions of the sheets, supported by the said rivets and dividing the space between the said sheets into longitudinal channels connecting the flow and return 5 chambers, said spacing-strips being bent to conform to the corrugations of the said sheets, substantially as specified.

In testimony whereof I have hereunto set my hand in presence of two subscribing witnesses.

WILLIS E. ROYS.
